UNITED STATES PATENT OFFICE.

CLIVE MORRIS ALEXANDER, OF NEW YORK, N. Y.

PROCESS AND APPARATUS FOR DECOMPOSING OILS.

Application filed October 9, 1919. Serial No. 329,625.

To all whom it may concern:

Be it known that I, CLIVE M. ALEXANDER, a citizen of the United States, residing at New York, in the county of New York, 5 State of New York, have invented certain new and useful Improvements in Processes and Apparatus for Decomposing Oils, and I do hereby declare the following to be a full, clear, and exact description of the invention, such as will enable others skilled in the art to which it appertains to make and use the same.

This invention relates to a process of decomposing oils; and it comprises a method 15 of forming light hydrocarbon oils from heavy hydrocarbon oils by thermal decomposition or "cracking," wherein liquid oil to be decomposed is sprayed into a heavier liquid oil which is maintained at a high 20 temperature, the sprayed oil which is contacted with the high temperature oil being decomposed into lighter hydrocarbons before vaporization takes place, such high temperature oil being circulated between a 25 heating vessel and a carbon deposition vessel.

The importance of processes for converting heavy hydrocarbon oils into light hydrocarbon oils which can be used as motor fuels is generally known. Many processes have 30 been invented and are in commercial use for this purpose. In all these methods of thermal decomposition the charge material is a distillate cut from crude oils, since the use of crude oil residuum is impractical 35 from the standpoint of coke formation. To make a distillate from the crude oil necessarily is an additional refining expense.

In the present invention, I charge fresh 40 crude oil through sprays immersed in residuum, at a high temperature, contained in a still. This spraying effects contact between fresh liquid oil and the high temperature liquid residuum in the still, and thereby causes its decomposition into light hydrocarbon oils before vaporization takes place. The residuum oil, of course, is of such 45 nature that it is stable at a temperature that is high enough to crack the fresh oil; this stability is due both to the presence of cyclic hydrocarbons and to colloidal carbon which is maintained in solution. While most of 50 the carbon is deposited in the carbon settling chamber, a small amount goes into the colloidal form. Very energetic agitation of the still content takes place, and as a result,

the carbon formed is broken up and maintained in suspension and constant movement. By attaching to the still a settling chamber, the liquid oil containing the carbon can be circulated from the still to the settling 60 chamber and back to the still, thereby effecting a removal of the carbon from the still continuously.

Under such conditions shutting down the still for cleaning out the carbon is not 65 frequent, and the resulting wear and tear on the still are not great. Residuum oils can be readily used and in fact are the most desirable since a high pressure on the still is not necessary to maintain the liquid phase 70 at decomposition temperature. With most residuum no pressure is required and very good results are obtained. However, when distillates are used, it is advantageous to use. 75

In a typical embodiment of this process, I continuously charge reduced mid-continent crude oil of about 26° Bé. gravity through sprays or atomizers immersed in liquid oil held at a cracking temperature 80 (say, 700° to 800° F.). This high temperature oil is contained in an ordinary still externally heated and is circulated from the still through a settling chamber and back to the still wherein the carbon formed 85 by decomposition in the still is deposited and the remaining oil pumped back to the still. The circulation of the high temperature oil is accomplished by a pump located 90 between the settling chamber and still and is maintained at such a rate that little carbon is deposited in the still.

Fresh oil is sprayed into the still at a rate equal to the rate of vaporization from the still, and a constant level of oil therein is 95 maintained.

Fractionating towers and condensers are attached to the still and the heavy fractions which are vaporized and condensed and are not available for motor fuels or illuminating oils are returned with fresh reduced crude and re-cracked. When pressure is used, there is not as much of the heavy fractions distilled as when no pressure is used. A very good gravity gasoline is formed by this process and carbon troubles 100 are reduced to a minimum.

This same process can be carried on without using the settling chamber but it is necessary to shut down the still from time 110

to time in order to clean out the accumulated carbon. In the preferred form, however, a separate carbon collecting chamber is used, and consequently most of the carbon, instead of settling in the bottom of the still, in a hard, dense heat-insulating layer, is carried out of the still and deposited in the settling chamber.

In the drawing I have illustrated diagrammatically an apparatus for carrying out the several steps of my invention. In this drawing, 1 indicates a still of usual form, supported in brick work or other convenient material, and heated in any desired manner.

15 Positioned within the still are a plurality of spraying devices 3, to which, through pipes 4 and 5, the oil that is to be cracked is led. This fresh oil is preferably pre-heated and is at a pressure high enough so 20 that it is atomized as it is injected into the still. These spraying devices 3 preferably spray the oil in a direction transverse with respect to the axis of the still 1. The sprays are also positioned near the bottom of the 25 still so as to produce a lively agitation at that point where the carbon ordinarily tends to collect.

By means of a pipe 6 the still is in communication with a carbon-separating chamber 7, which may be of any desired design, its purpose being to allow the carbon that is carried into it mixed with the oil to settle, while the carbon-free oil passes from the chamber 7 to pipe 8 through a 30 circulating pump 9, thence to pipe 10 and back to the still 1.

The oil in the still 1 is a very heavy residuum oil, and is maintained at a temperature of say 700° to 800° F. The oil level in 40 the still 1 and the carbon-separating chamber 7 is substantially the same, an equalizing pipe 11 being connected to the chamber 7 and still 1 to balance the pressure.

The lighter hydrocarbon vapors resulting 45 from the cracking are led from the still 1 by means of a pipe 12 to an ordinary fractionating tower 13; thence through a pipe 14 to a condenser 15 of any suitable design.

The still 1 may be operated at high or 50 low pressure. The usual residuums work satisfactorily at low pressure, while with certain distillates, pressure may be used. A pressure regulating valve for the still is shown at 16.

55 The condenser similarly is operated at high or low pressure, dependent on particular conditions. A pressure controlling valve for the condenser is indicated at 17.

The condensate from the fractionating 60 tower 13 may be continuously run back into the still and distributed over the hot oil contained therein through the perforated distributing pipe 18. This will be the usual method of operation when the pressure is 65 controlled at 17. When the pressure is con-

trolled at 16, the condensate from the fractionating tower 13 usually goes direct to the pump charging fresh residuum to the still.

As a matter of practice, a battery of stills 70 1 may be used, they being interconnected so that the residuum oil flows directly from one still to the next and eventually into a carbon-separator 7, and thence through a circulating pump that is effective in circulating the oil through the whole battery of stills.

75 The important point of the invention is spraying the oil that is to be cracked into a bath of highly heated oil, the spraying 80 device being immersed in the highly heated oil so that it is kept in rapid circulation and the deposition of carbon prevented. As a corollary to the above, the heavy high 85 temperature oil is circulated from the still through a carbon-collecting chamber and thence back to the still, having deposited its carbon in the carbon-collector.

90 It should be understood that the essential features of the invention may be carried out in other ways than in the particular apparatus shown.

In some cases, a pressure of 5 to 6 atmospheres may be maintained on the still; and from 1 to 2 atmospheres on the 95 condenser.

I claim as my invention:

1. A process of decomposing oil, comprising injecting a lighter oil in an atomized liquid form below the surface of a bath of 100 heavy oil, heated to a temperature sufficient to decompose the lighter oil, at such a depth that the lighter oil will be cracked before vaporization, collecting the oil formed as the result of the cracking, leading 105 said heavy oil from the still, removing the carbon therefrom and returning it to the still.

2. A process of decomposing oil, comprising injecting a lighter oil in an atomized 110 liquid form below the surface of a bath of heavy oil heated to a temperature sufficient to decompose the lighter oil at such a depth that the lighter oil will be cracked before vaporization in a still, and circulating the said heavy oil from the still to a carbon-removing device and then back to the still.

115 3. A process of decomposing oil, comprising injecting oil to be cracked into a bath of 120 highly heated heavy oil in a still and below the liquid level of said heavy oil, at such a depth that the lighter oil will be cracked before vaporization whereby the heavy oil is agitated, leading the said heavy oil to a carbon-removing device, and collecting the oil formed as the result of the cracking.

4. A process of decomposing oil, comprising injecting oil to be cracked into a bath of 125 highly heated heavy oil in a still and below

the liquid level of said heavy oil, at such a depth that the lighter oil will be cracked before vaporization whereby the heavy oil is agitated, leading the said heavy oil to a 5 carbon-removal chamber, and thence back into the still, and collecting the lighter oil formed as the result of the cracking.

5. A process of decomposing oil, comprising heating a heavy oil in a still to a temperature sufficient to decompose a lighter oil but insufficient to decompose said heavy oil, injecting a lighter oil into said heavy oil below the liquid level of said heavy oil at such a depth that the lighter oil will be 10 cracked before vaporization so as to agitate the heavy oil and keep the free carbon therein in suspension, leading the heavy oil from said still, removing the carbon therefrom, and returning it to the still.

20 6. A process of decomposing oil, comprising heating a heavy oil in a still to a temperature sufficient to decompose a lighter oil but insufficient to decompose said heavy oil, injecting a lighter oil into said heavy oil 25 near the bottom of the still and at such a depth that cracking will result before vaporization so as to agitate the heavy oil and keep the free carbon therein in suspension, leading the heavy oil from said still, removing the carbon therefrom, and returning it to the still.

7. An apparatus for decomposing oil, comprising a still containing heavy oil, means to heat said still, nozzle means immersed in the heavy oil for injecting a 35 lighter oil in liquid form into said heavy oil, a carbon-removing chamber connected to said still so that the heavy oil level is substantially the same in said carbon-removing chamber and said still, and means to 40

circulate the heavy oil through the said chamber and back to the still.

8. A process of cracking oil, comprising heating a bath of residuum oil to a temperature sufficient to crack a lighter oil, but not 45 sufficient to cause a cracking of the residuum oil, injecting a lighter oil in an atomized, liquid state into the residuum oil below the liquid level thereof, whereby it is cracked while in the liquid state by the high 50 temperature of the residuum oil, such injection of the lighter oil serving to agitate the residuum oil, to prevent the deposition of carbon, and collecting the oils formed as the 55 result of the cracking.

9. A process of cracking oil, comprising heating a bath of heavy oil to a temperature sufficient to cause the cracking of a lighter oil, but not sufficient to cause the cracking of the heavy oil, injecting a lighter oil in 60 an atomized liquid state below the surface of the heavy oil, whereby the light oil is cracked while in the liquid state, and collecting the lighter oils formed as the result 65 of such cracking.

10. A process of cracking oil, comprising heating a bath of heavy oil to a temperature sufficient to cause the cracking of a lighter oil, but not sufficient to cause the cracking of the heavy oil, injecting a lighter oil in 70 an atomized liquid state below the surface of the heavy oil, whereby the light oil is cracked while in the liquid state, collecting the lighter oils formed as the result of such cracking, and circulating the heavy oil 75 through a carbon removing device and back into the still.

In testimony whereof I affix my signature.

OLIVE MORRIS ALEXANDER.
